REINHARD HILDEBRAND, OF WEBSTER GROVES, MISSOURI, ASSIGNOR OF ONE-HALF
TO GEORGE D. POGUE, OF PHILADELPHIA, PENNSYLVANIA.

REVERSING MECHANISM FOR INTERNAL-COMBUSTION ENGINES.

1,356,820.

Specification of Letters Patent. Patented Oct. 26, 1920.

Application filed June 2, 1919. Serial No. 301,256.

To all whom it may concern:

Be it known that I, REINHARD HILDEBRAND, a citizen of Germany, residing at Webster Groves, Missouri, have invented a certain new and useful Improvement in Reversing Mechanisms for Internal-Combustion Engines, of which the following is a full, clear, and exact description, such as will enable others skilled in the art to which it appertains to make and use the same.

This invention relates to reversing mechanisms of the kind that are used in connection with marine internal combustion engines for changing the direction of rotation of the crank shaft, and particularly to reversing mechanisms of the type in which the change in the direction of rotation of the crank shaft is effected by changing the relationship between the rocker arms or valve actuating devices and two separate and distinct sets of cams on the cam shaft, one of which sets coöperates with the rocker arms when the crank shaft is rotating forwardly and the other when the crank shaft is rotating rearwardly.

One object of my invention is to provide an inexpensive reversing mechanism for internal combustion engines which does not comprise a materially greater number of parts than the reversing mechanisms used on stationary engines.

Another object is to provide a reversing mechanism which is so constructed and combined with the controlling mechanism for the engine that the fuel valve which regulates the supply of fuel to the engine has to be closed before the reversing mechanism can be operated.

Another object is to provide a reversing mechanism that comprises a single controlling member hereinafter referred to as a reversing member, which, upon being moved by the operator in charge of the engine, renders the rocker arms inoperative with relation to the set of cams on the cam shaft with which they have been coöperating, trips a locking mechanism which holds said cams in alinement with said rocker arms, causes the other set of cams to be brought into alinement with said rocker arms and thereafter brings the rocker arms into operative position with relation to said second set of cams and also causes said cams and

rocker arms to be locked in alinement with each other.

And still another object is to provide a reversing mechanism of the character just referred to, which is so constructed that the operator in charge of the engine can easily determine whether or not the coöperating parts or elements of same are functioning properly while the reversing member is being moved from one position to another. Other objects and desirable features of my invention will be hereinafter pointed out.

In the preferred form of my invention, as herein shown, the operative and inoperative relationships between the rocker arms and the cams on the cam shaft are established by moving the fulcrums of all of the rocker arms simultaneously relatively to the cam shaft, the alinement of the rocker arms with the two sets of cams on the cam shaft is effected by shifting the cam shaft longitudinally and the locking of the rocker arms in alinement with one or the other set of cams on the cam shaft is obtained by means of a locking device that coöperates with the cam shaft. I wish it to be understood, however, that my invention is not limited to a reversing mechanism of the particular design or construction herein illustrated, as my broad idea consists in a reversing mechanism comprising a reversing member, which, upon being moved by the operator in charge of the engine, produces the following results,—namely, renders all of the rocker arms inoperative relatively to one set of cams on the cam shaft, trips the locking means that governs the alinement of the rocker arms with said cams, causes the other set of cams to be brought into alinement with the rocker arms and then renders the rocker arms operative with relation to said cams and restores the locking means to its operative position. The rocker arms are preferably carried by an eccentrically mounted fulcrum member which is combined with the reversing member in such a manner that said fulcrum member will be moved sufficiently to disengage the rocker arms from the cams with which they have been coöperating when said reversing member starts to move from one position into another, and the means for shifting the cam shaft longitudinally preferably consists of a double acting servo motor directly con-

nected with the cam shaft, or two single acting servo motors arranged at the opposite ends of the cam shaft and directly connected with same. The servo motor or servo 5 motors may either be operated by electricity or a medium under pressure, and the device or devices which control the operating medium for said motors are combined with the reversing member of the mechanism in such 10 a manner that they will be directly controlled by said reversing member. The locking means that holds the cam shaft in either of its two positions is also combined with the reversing member in such a manner 15 that said locking means will be rendered inoperative and then restored to its normal position while the reversing member is being moved from one position to the other. Any preferred type of controlling means 20 may be used for governing the operation of the engine, but the reversing member is combined with the controlling means in such a manner that the fuel valve which governs the supply of fuel to the engine 25 will have to be closed before the reversing member can be moved to change the direction of rotation of the crank shaft of the engine.

Figure 1 of the drawings is a front elevational view of a marine internal combustion engine of the Diesel type equipped with a reversing mechanism constructed in accordance with my invention.

Fig. 2 is a vertical cross sectional view of 35 said engine.

Fig. 3 is an enlarged detail view, illustrating one of the rocker arms and the two cams on the cam shaft that coöperate with said rocker arm.

Fig. 4 is a view taken at right angles to Fig. 3.

Fig. 5 is a detail view, illustrating the locking means for the cam shaft.

Fig. 6 is a detail sectional view of one of 45 the servo motors.

Fig. 7 is a side elevational view of the reversing member, the controlling mechanism for the engine and certain of the parts that are combined with and directly operated by the reversing member.

Fig. 8 is a front elevational view of the parts shown in Fig. 7.

Fig. 9 is a vertical sectional view, taken on the line 9—9 of Fig. 7; and

Fig. 10 is a horizontal sectional view, taken approximately on the line 10—10 of Fig. 7.

Referring to the drawings which illustrate the preferred form of my invention. 60 1 designates the rocker arms or valve operating devices of a marine internal combustion engine of the Diesel type. A designates a cam shaft provided with cams that actuate the rocker arms 1, and 2 designates the 65 crank shaft of the engine which is opera-

tively connected in any suitable manner with the cam shaft A. In the engine herein shown the cam shaft A is composed of two sections *a* that are joined together by a coupling device *a'*, as shown in Fig. 1, 70 said coupling device being inclosed in a hollow gear *2^a* that forms part of the mechanism for transmitting movement from the crank shaft 2 of the engine to the cam shaft A. In order that the direction of rotation 75 of the crank shaft 2 may be reversed, the cam shaft A is provided with a set of cams 3 that are adapted to be brought into alinement with the rocker arms 1 when it is desired to have the crank shaft of the engine 80 rotate forwardly, and a separate and distinct set of cams 4 that are adapted to be brought into alinement with said rocker arms when it is desired to have said crank shaft rotate rearwardly, the cam shaft A being normally 85 arranged either in one position, which I will refer to as its "ahead" position, or in another position, which I will refer to as its "astern" position.

My invention consists in a reversing 90 mechanism for changing the relationship between the rocker arms and the cams on the cam shaft so as to cause said rocker arms to coöperate with either set of cams at the will of the operator in charge of the engine. 95 In the preferred form of my invention, as herein shown, two cams 3 and 4 are provided for each of the rocker arms 1 and all of the rocker arms are pivotally mounted on a common fulcrum member consisting of a shaft 100 B that is arranged parallel to the cam shaft A, as shown in Fig. 3. The rocker arms 1 are rendered operative and inoperative with relation to the cams on the cam shaft A by turning the fulcrum member B relatively to 105 the cam shaft so as to move the rollers 1^a on the rocker arms 1 into or out of the path of movement of the operative set of cams on the cam shaft. In the form of my invention herein illustrated the fulcrum member B 110 consists of an eccentrically mounted shaft, which, upon being rotated in the direction indicated by the arrow in Fig. 3, causes the rollers 1^a on the rocker arms to be moved upwardly out of the path of the set of cams 115 on the cam shaft which are then in alinement with said rocker arms. After the rocker arms have been rendered inoperative with relation to the cams, as just referred to, the cam shaft A is moved longitudinally 120 so as to shift the other set of cams on the cam shaft into alinement with the rocker arms. If, for example, the cams 3 are co-operating with the rocker arms and it is desired to reverse the engine, the operator in charge of the engine actuates a means that causes the rocker arm shaft or fulcrum member B to move into the position shown in dotted lines in Fig. 3 and the cam shaft A to move longitudinally into such a posi- 125 130

tion that the cams 4 thereon will coöperate with the rocker arms 1 when the fulcrum member B is thereafter restored to its normal position shown in full lines in Fig. 3.

5 The rotary movement of the rocker arm shaft B and the longitudinal movement of the cam shaft A are effected by moving a controlling member or reversing member C that is arranged at the front of the engine 10 in proximity to the operator in charge of the engine. Said reversing member C is secured to the front end of a horizontally-disposed shaft 5 which is provided with a gear 6 that meshes with a gear 7 secured to a 15 shaft 8 arranged at right angles to the reversing shaft 5, as shown in Figs. 7 and 10, and provided with an arm 9 to which an operating link 10 is connected. The upper end of the link 10 is pivotally connected to 20 a lever 10^a that is joined by means of a link 10^b to an arm 11 on the rocker arm shaft B, thus forming a connection between the rocker arm shaft and the reversing shaft 5 which causes the rocker arm shaft to turn 25 when the reversing member C is moved, as hereinafter described. The means herein illustrated for moving the cam shaft A longitudinally consists of two servo motors D and D' arranged at the opposite ends of the 30 cam shaft A, as shown in Fig. 1, and connected directly with said cam shaft so as to cause said shaft to move longitudinally in one direction when the servo motor D operates and to move longitudinally in the opposite direction when the servo motor D' operates. Said servo motors can either be electrically operated or operated by a medium under pressure, and instead of using two 35 single acting servo motors, a double acting servo motor could be used without departing from the spirit of my invention. The servo motors herein illustrated are adapted to be operated by compressed air or any other suitable medium under pressure, and each of 40 said motors comprises a cylinder 12, preferably formed integral with the end wall 13 of the cam shaft housing 14, a piston 15 reciprocatingly mounted in said cylinder and arranged so that it bears directly against 45 one end of the cam shaft A, and a hollow stem 15^a on said piston that reciprocates in a hollow guide 16 on the head 16^a of the cylinder 12, as shown in Fig. 6. A medium under pressure is admitted to the servo motor 50 through a supply pipe 17 that is connected with the hollow guide 16 on the head of the cylinder of the servo motor, and said operating medium is discharged from said hollow guide through the pipe 17 and through 55 a vent or leak groove in the stem of the valve that controls the supply of the operating medium to the pipe 17. The cylinder 12 of the servo motor has a discharge port 18 which is preferably provided with a cock or 60 similar device 19 that can be adjusted so as

to regulate the escape of the air from the cylinder 12. A coiled compression spring 20 is preferably arranged in the hollow guide 15^a on the piston 15 so as to constantly exert a light pressure on said piston in a direction tending to hold it in engagement with the cam shaft A. Controlling valves 21 and 22 are provided for governing the supply of the operating medium to the servo motors D and D', which valves are arranged 70 in valve casings 21^a and 22^a located at the rear side of the engine, as shown in Figs. 2, 7 and 9, the operating medium being conducted to said valve casings by a supply pipe 170. The pipe 17 previously referred 75 to, through which the operating medium is supplied to the servo motor D, leads to the valve casing 21^a, as shown in Fig. 9, and the pipe 17^a, through which the operating medium is supplied to the servo motor D', leads 80 to the valve casing 22^a, the stems of the valves 21 and 22 being provided with leak grooves 21^d and 22^d, as shown in Fig. 9, through which the operating medium escapes from the pipes 17 and 17^a after said 85 valves have closed. The valves 21 and 22 are normally held seated by the pressure in the supply pipe 170, and the reversing shaft 5 is provided with a cam 23 which operates with rollers on valve levers 21^c and 22^c that open the valves 21 and 22, respectively. 90

The cam shaft A is normally locked either in its ahead position or in its astern position by means of a locking device E, shown 100 in Figs. 4 and 5, which coöperates with a collar E' on the cam shaft A provided with two grooves 24 and 24^a. Said locking device E is pivotally connected at 25 to a bracket 26 on the cam shaft housing 14, and means is provided for moving said locking device E upwardly into an inoperative position, as shown in broken lines in Fig. 5, when the rocker arm shaft B is turned to render the rocker arms 1 inoperative and for moving 105 said locking device E downwardly to its operative position when said rocker arm shaft B is restored to its former position, the means herein illustrated for actuating the locking device E consisting of a link 27 that connects said locking device with an arm 28 on the rocker arm shaft B. When the crank shaft of the engine is rotating forwardly the reversing member C occupies 110 such a position that a pointer or indicating device 29 thereon, shown in Fig. 8, stands opposite the word "ahead" on the stationary quadrant 30. To reverse the engine the operator turns the reversing member C to the left until the indicator 29 thereon stands opposite the word "astern" on the quadrant 30. The quadrant 30 is provided with the word "neutral" at a point midway the words "ahead" and "astern" so as to enable the operator to determine when the reversing shaft 115 120 125 130

5 occupies such a position that the rollers 1^a on the rocker arms 1 are out of the path of the cams on the cam shaft A, when the locking device E is in its inoperative position 5 and when the cam 23 stands in the position in Fig. 9.

If desired, a visual indicator F may be employed so as to show at all times the position of the cam shaft A, the indicator F 10 herein shown consisting of a hand or pivotally mounted device arranged in proximity to the quadrant 30 so that it will point to the words "ahead," "neutral" and "astern" on said quadrant, depending upon 15 the position of the cam shaft, said indicator F being secured to a shaft provided with an arm 31 that is joined by means of a link 32 to an arm 33 secured to one member of a reduction gearing, indicated as an entirety 20 by the reference character 34 in Fig. 1, that is operatively connected by means of a rack bar 35 to a yoke or fork 36 which fits in a groove in the cam shaft A. When the crank shaft of the engine is rotating forwardly the 25 indicator F will occupy such a position that it points to the word "ahead" on the quadrant 30, and when the cam shaft A is shifted longitudinally into its astern position, the indicator F will swing to the right, 30 looking at Fig. 8, into such a position that it will point to the word "astern" on the quadrant.

The fuel pump that regulates the supply of liquid fuel to the engine and the means for 35 controlling the starting air and for governing the operation of the distributing valves of the engine have not been illustrated, as they form no part of my present invention. The controlling member, however, which 40 governs the fuel pump, starting air and distributing valves is herein illustrated as a hand wheel G that is arranged in proximity to the reversing member C. Said controlling wheel G has to make four distinct 45 movements in starting the engine, each movement being approximately a quarter turn. Assuming that the engine is at rest and it is desired to start the engine, the first quarter turn of the controlling member G 50 admits compressed air to the starting valves of all of the cylinders, thereby causing the engine to start. When the engine has gained a certain speed the controlling member G is given a second quarter turn which 55 shuts off the starting air from some of the cylinders and causes said cylinders to be supplied with fuel. After these cylinders have started to fire the controlling member G is given another quarter turn so as to completely 60 shut off the starting air and cause all of the cylinders to be supplied with fuel, thereby causing the engine to generate its maximum power at the end of the third quarter turn of the controlling wheel G. 65 Any further turning of the controlling

wheel G will gradually diminish the fuel supply to all of the cylinders, and thus gradually reduce the power of the engine until the controlling wheel G has completed its complete cycle, at which time the fuel 70 will be completely cut off, thus causing the engine to stop. Accordingly, the last quarter turn of the controlling member G is used exclusively to regulate the speed of the engine, and during this last quarter turn the 75 wheel G may be turned in either direction to increase or diminish the power produced by the engine. During the first three quarter turns of the controlling wheel G, however, a ratchet mechanism operates to prevent the wheel G from being turned rearwardly after it has been started on its cycle. In order to prevent the operator from moving the reversing member C without first cutting off the supply of fuel to the engine, 80 means is provided for interlocking the reversing member C with the controlling member G of the engine in such a manner that said reversing member can not be moved unless the controlling member G 85 stands in a certain position. The interlocking device herein illustrated comprises one or more disks 37 on the reversing shaft 5, each of which is provided with two flattened sides 37^a, as shown in Fig. 8. The 90 vertically-disposed shaft 38, to which the controlling wheel G is connected, is arranged in vertical alinement with the reversing shaft 5 and is provided at its lower end with an oblong-shaped member 39 that 95 is adapted to coöperate with the disks 37. The member 39 and the disks 37 are so formed and arranged that when the engine is in normal operation the member 39 stands crosswise of the disks 37, thereby preventing the reversing member C from being turned without first moving the controlling member G to cut off the supply of fuel and arrange the member 39 in parallel relation with the disks 37, as shown in Fig. 10. 100 When the reversing member C stands in either its ahead position or in its astern position the controlling member G can be operated due to the fact that the flattened sides of the disks 37 lie below the member 37. 105 When the reversing member stands in its neutral position, however, as shown in Figs. 7, 8 and 10, the disks embrace the member 39, and thus prevent the controlling member G from being operated. Consequently, 110 it is impossible to start the engine when the reversing mechanism is in an improper position, namely, in such a position that one or the other set of cams on the cam shaft A is not in alinement with the rocker arms 1 115 and it is impossible for the operator in charge of the engine to reverse the engine before he has turned off the supply of fuel to the engine, or at least, turned the controlling wheel G far enough on the last 120 125 130

quarter turn turn of its cycle to greatly reduce the speed of the engine.

From the foregoing it will be seen that my improved reversing mechanism is so constructed that in the operation of reversing the engine the rollers on the rocker arms are first removed from the set of cams on the cam shaft with which they have been coöperating, the cam shaft is then shifted longitudinally so as to bring the other set of cams thereon into alinement with the rocker arms and thereafter the rollers on the rocker arms are brought into position to coöperate with said second set of cams. The movement of the rocker arms into and out of operative position with relation to the cams on the cam shaft is effected by bodily moving the shaft B on which all of the rocker arms are fulcrumed, and the longitudinal shifting of the cam shaft is effected either by means of a double acting servo motor directly connected with the cam shaft, or by means of two single acting servo motors arranged at the opposite ends of the cam shaft and directly connected with same. When two single acting servo motors of the type herein illustrated are employed, one servo motor will act as a dash pot or retarding device to prevent the cam shaft from moving too abruptly, due, of course, to the fact that the longitudinal movement of the cam shaft causes the piston of the inoperative servo motor to move toward the head of the cylinder of said motor, and thus gradually expel the air in the dash pot of said cylinder through the leak port or discharge opening 18 leading from said cylinder. During the actual running of the engine the pipes 17 and 17^a leading from the casings of the controlling valves to the cylinders of the servo motors are vented by the leak grooves 21^d and 22^d in the stems of the valves 21 and 22, respectively. It is only during the operation of reversing the engine that the operating medium is supplied to the servo motors. At all other times the controlling valves 21 and 22 are seated so as to cut off communication between the supply of operating medium and the cylinders of the servo motors.

Assuming that the crank shaft of the engine is rotating forwardly, the indicator 29 on the reversing member C stands opposite the word "ahead" on the quadrant 30, the rocker arms 1 are in operative position with relation to the cam shaft, the cams 3 on said cam shafts are in alinement with said rocker arms and the locking device E is in engagement with the groove 24 of the collar E' on the cam shaft A. To reverse the engine the operator first turns the controlling wheel G so as to cut off the supply of fuel to the engine and arrange the substantially oblong-shaped member 39 on the lower end of the controlling shaft 38 in parallel relation with

the disks 37 on the reversing shaft. He then turns the reversing member C in anti-clockwise direction from its ahead position through its neutral position and into its astern position. The movement of said reversing member C from its ahead into its neutral position causes the rocker arm shaft B to turn in the direction indicated by the arrow in Fig. 3, thereby rendering all of the rocker arms 1 inoperative with relation to the cam shaft and also causing the locking device E to be moved upwardly out of locking engagement with the cam shaft. This movement of the reversing member C, namely, from its ahead to its neutral position, causes the cam 23 on the reversing shaft 5 to wipe past the spring-pressed valve lever 21^c that coöperates with the valve 21 without, however, opening or unseating said valve 21, due, of course, to the fact that the cam 23 engaged the valve lever 21^c and moved it downwardly away from the lower end of the stem of the valve 21. Just before the cam 23 reaches the neutral position shown in Fig. 9 the valve lever 21^c snaps upwardly into engagement with the stem of the valve 21. As shown in Fig. 9 the valve levers 21^c and 22^c are combined with springs 21^b and 22^b that normally hold said levers in engagement with the stems of their respective valves. During the second part of the movement of the reversing member C from its neutral into its astern position the cam 23 on the reversing shaft 5 engages the valve lever 22^c and moves said valve lever in a direction to unseat the valve 22, thereby causing compressed air to be admitted to the servo motor D' so as to cause the piston of said motor to move the cam shaft A longitudinally to the left, looking at Fig. 1, and thus bring the cams 4 on said cam shaft into alinement with the rocker arms 1. The valve 22 seats or closes as soon as the cam 23 passes out of engagement with the roller on the valve lever 22^c, and while the cam shaft is moving longitudinally in the direction previously referred to, the servo motor D acts as a dash pot to retard the movement of the cam shaft and prevent it from moving abruptly from its ahead into its astern position. By the time the cam shaft reaches its astern position the arm 9, which is connected by means of the gears 6 and 7 with the reversing shaft 5, will have been brought into such a position that the rocker arms are restored to operative relationship with the cams 4 on the cam shaft and the locking device E moved into engagement with the groove 24^a in the collar E' on the cam shaft. It will thus be seen that in my improved reversing mechanism a single manipulation of the reversing member C either from its ahead position to its astern position or from its astern position to its ahead position successively operates the various elements that

effect a change in the direction of rotation of the crank shaft of the engine. This is a very desirable feature of a reversing mechanism for internal combustion engines, as it is exceedingly simple; it is inexpensive to manufacture; and it is simple to understand and operate.

The locking device E is preferably so constructed that it will be out of engagement with the cam shaft during the major portion of the time, when the reversing member C is moving from its neutral into its ahead position or into its astern position. This is a desirable feature, in that it gives ample time for the servo motor which is then operating to shift the cam shaft longitudinally. In case the reversing member C is moved too quickly, or in case the servo motor which is then operating is too sluggish, the locking device E will engage the collar E' on the cam shaft without entering one of the grooves in said collar. No damage results, however, to any of the parts of the mechanism, because it is impossible for the operator to complete the movement of the reversing member C or move it into its final position until the cam shaft A reaches such a position that the locking device E is in alignment with the proper groove in the collar E' on the cam shaft. Accordingly, the locking device E, in addition to securely locking the cam shaft in one or the other of its positions, also enables the operator in charge of the engine to determine whether or not the servo motors are acting properly, for if the servo motor that is operative is sluggish, it will be impossible for the operator to turn the reversing member C into its final position. This additional function of the locking device E is not relied upon, however, to insure the proper operation of the mechanism, for the visual indicator F constitutes a means that enables the operator to see at all times just how the servo motors are acting, for when the cam shaft has reached one or the other of its normal positions, the indicator F will point either to the word ahead or astern on the quadrant.

Having thus described my invention, what I claim as new and desire to secure by Letters Patent, is:

1. An internal combustion engine provided with valve operating devices, an operating means for said devices comprising two sets of cams, one of which sets coöperates with said devices when the crank shaft of the engine is rotating forwardly and the other when the crank shaft is rotating rearwardly, a reversing member, mechanism operated by said reversing member for rendering said valve operating devices inoperative with respect to the cams with which they have been coöperating when said reversing member moves from one of its positions to its other position, a motor adapted

to be actuated by an operating medium for causing the other set of cams to be brought into alinement with said devices, and means governed by said reversing member for controlling the medium used to operate said motor.

2. An internal combustion engine provided with valve operating devices, an operating means for said devices comprising two sets of cams, one of which sets alines with said devices when the crank shaft of the engine is rotating forwardly and the other set alining with said devices when the crank shaft is rotating rearwardly, a locking means for holding said valve operating devices in alinement with one or the other set of cams, a reversing member that normally occupies one of two positions, and means whereby the movement of said reversing member from one position to another renders said valve operating devices inoperative with respect to the cams with which they have been coöperating, renders said locking means inoperative, causes the other set of cams to be brought into alinement with said valve operating devices and finally establishes operative relationship between said valve operating devices and said second set of cams and also renders said operating mechanism operative.

3. An internal combustion engine provided with a controlling member for governing the operation of the fuel pump, starting air and distributing valves of the engine, a reversing member that normally occupies one of two positions, means for causing the direction of rotation of the crank shaft of the engine to be reversed when said reversing member is moved from one of its positions to its other position, and means for preventing said controlling member from being actuated while said reversing member is being moved from one of its positions to its other position or when it is standing in an intermediate position.

4. An internal combustion engine provided with a controlling member for governing the operation of the fuel pump, starting air and distributing valves of the engine, a reversing member that normally occupies one of two positions, means for causing the direction of rotation of the crank shaft of the engine to be reversed when said reversing member is moved from one of its positions to its other position, and means for preventing said reversing member from being operated or moved before the controlling member has been actuated to cut off the supply of fuel to the engine or materially reduce the speed of the engine.

5. An internal combustion engine, comprising valve actuating devices, an operating means for said devices comprising one group of elements that coöperate with said devices to cause the crank shaft of the engine

- to rotate forwardly and another group of elements that coöperate with said devices to cause said crank shaft to rotate rearwardly, a reversing member, a mechanical means actuated by said reversing member 5 for rendering the valve actuating devices inoperative with relation to one of said groups of elements, a motor adapted to be actuated by a medium under pressure for moving the 10 other group of elements into operative position with relation to said devices, and means operated by said reversing member for controlling the medium that actuates said motor of elements.
- 15 6. An internal combustion engine, comprising rocker arms for operating the valves of the engine, a cam shaft provided with two sets of cams, one or the other of which sets is normally in alinement with said 20 rocker arms, a locking device for said cam shaft operatively connected with said rocker arms, means for rendering said rocker arms inoperative with relation to the cams that are arranged in alinement with same and 25 also rendering said locking device in operative, and means for bringing the rocker arms into alinement with the other set of cams for changing the direction of rotation of the crank shaft of the engine, the means 30 that previously rendered said rocker arm inoperative causing said rocker arms and locking device to be rendered operative after said arms have been brought into alinement with said second set of cams.
- 35 7. An internal combustion engine provided with rocker arms for actuating the valves of the engine, a cam shaft provided with two sets of cams, a locking means for holding said cam shaft in such a position 40 that one or the other sets of cams thereon will aline with said rocker arms, means for rendering said locking means inoperative, and means for shifting said cam shaft longitudinally so as to move one of the sets of 45 cams thereon out of alinement with the rocker arms and bring the other set of cams into alinement with the rocker arms.
8. An internal combustion engine, comprising rocker arms for actuating the valves 50 of the engine, a shaft on which all of said rocker arms are fulcrumed, a shiftable cam shaft provided with two sets of cams that are adapted to coöperate with said rocker arms, and means for moving said rocker 55 arms shaft bodily relatively to said cam shaft so as to render the rocker arms inoperative with relation to the cams on the cam shaft preparatory to shifting the cam shaft.
- 60 9. An internal combustion engine, comprising rocker arms for actuating the valves of the engine, an eccentrically mounted shaft 65 on which said rocker arms are fulcrumed, a shiftable cam shaft provided with separate and distinct sets of cams that are adapt-
- ed to coöperate with said rocker arms, and means for turning said rocker arm shaft so as to bodily shift same and thus render the rocker arms operative or inoperative with relation to said cams. 70
10. An internal combustion engine provided with rocker arms for actuating the valves of the engine, a fulcrum member common to all of said rocker arms, a cam shaft provided with two sets of cams for coöperating with said rocker arms, one or the other of which sets is adapted to coöperate with the rocker arms, depending upon the direction of rotation of the crank shaft of the engine, means for moving said fulcrum member first in one direction to render the rocker arms inoperative and thereafter back to normal position to render said rocker arms operative, and means separate and distinct from said fulcrum member and operated independently of same for shifting the cam shaft longitudinally when the rocker arms are inoperative so as to move one set of cams out of alinement with the rocker arms and the other set of cams into 85 alinement with said rocker arms.
11. An internal combustion engine provided with rocker arms for actuating the valves of the engine, a fulcrum member common to all of said rocker arms, a cam shaft 90 provided with two sets of cams for coöperating with said rocker arms, one or the other of which sets is adapted to coöperate with the rocker arms, depending upon the direction of rotation of the crank shaft of the engine, means for moving said fulcrum member first in one direction to render the rocker arms inoperative and thereafter back to normal position to render said rocker arms operative, means for shifting the cam 95 shaft longitudinally when the rocker arms are inoperative so as to move one set of cams out of alinement with the rocker arms and the other set of cams into alinement with said rocker arms, a locking device for said 100 cam shaft, and means for rendering said locking device inoperative when the fulcrum member is moved to render the rocker arms inoperative and for moving said locking device back into engagement with the cam 105 shaft when said fulcrum member is restored to its normal position.
12. An internal combustion engine provided with rocker arms for actuating the valves of the engine, a shiftable cam shaft 110 provided with two sets of cams for coöperating with said rocker arms, a piston that bears directly against one end of said cam shaft and shifts it longitudinally so as to change the relationship between said rocker 115 arms and the cams on said shaft, and means for supplying an operating medium to the cylinder in which said piston is arranged.
13. An internal combustion engine, comprising rocker arms or valve operating de- 120
- 130

- vices, a cam shaft provided with a plurality of sets of cams for coöperating with said rocker arms, servo motors arranged at the opposite ends of said cam shaft for shifting said shaft longitudinally so as to change the relationship between the rocker arms and the cams on said shaft, a manually-operable reversing member, means for rendering said rocker arms inoperative with relation to said cam shaft during the first part of the movement of said reversing member, and an independent means governed by said reversing member for thereafter supplying one of said servo motors with an operating medium.
14. An internal combustion engine, comprising rocker arms or valve operating devices, a cam shaft provided with a plurality of sets of cams for coöperating with said rocker arms, and a shifting means for said shaft comprising devices arranged at the opposite ends of said shaft and each composed of a cylinder and a piston in said cylinder that bears against one end of the cam shaft, one of said devices acting as a dash pot to retard the movement of said cam shaft when the piston of the other device is moving under the influence of an operating medium supplied to its cylinder.
15. An internal combustion engine, comprising rocker arms or valve operating devices, an eccentrically mounted shaft on which all of said rocker arms are fulcrumed, a shiftable cam shaft provided with two sets of cams for coöperating with said rocker arms, servo motors arranged at the opposite ends of said cam shaft for shifting it longitudinally, a reversing member, a mechanical connection between said reversing member and rocker arm shaft for turning said rocker arm shaft so as to disengage the rocker arms from the camis, and an independent means governed by said reversing member for causing one of said servo motors to operate so as to shift the cam shaft longitudinally.
16. An internal combustion engine, comprising rocker arms or valve operating devices, an eccentrically mounted shaft on which all of said rocker arms are fulcrumed, a shiftable cam shaft provided with two sets of cams for coöperating with said rocker arms, a locking device that is capable of holding said cam shaft in either one of two positions, servo motors arranged at the opposite ends of said cam shaft for shifting it longitudinally, a reversing member that normally stands in either one of two positions, and means operated by said reversing member for turning said rocker arm shaft in a direction to render the rocker arms inoperative, for disengaging the locking device from said cam shaft, for causing one of the servo motors to shift the cam shaft longitudinally and for restoring the rocker arm shaft and the locking device to their normal positions when said reversing member is

moved from one of its positions to its other position.

17. An internal combustion engine, comprising rocker arms or valve operating devices, a shiftable cam shaft provided with two sets of cams for coöperating with said rocker arms, means for shifting said cam shaft in opposite directions so as to change the direction of rotation of the crank shaft of the engine, a locking device for said cam shaft, a reversing member, and elements controlled by said reversing member for governing the operation of said shifting means, said locking device being so constructed that said reversing member can not be moved to its final position until after said cam shaft has reached its final position during the operation of shifting said shaft.

18. An internal combustion engine, comprising rocker arms or valve operating devices, a shiftable cam shaft provided with two sets of cams for coöperating with said rocker arms, single acting servo motors arranged at the opposite ends of said shaft for shifting it longitudinally in opposite directions, valves for governing a medium used to actuate said servo motors, a reversing member that normally stands in one of two positions, a mechanical means actuated by said reversing member for rendering said rocker arms inoperative with relation to the cams on said cam shaft, and an independent means actuated by said reversing member for causing one of said valves to operate when said reversing member is moved from one position to the other and for causing the other valve to operate when said reversing member is restored to its former position.

19. An internal combustion engine, comprising rocker arms or valve operating devices, an eccentrically mounted shaft on which said rocker arms are fulcrumed, a shiftable cam shaft provided with two sets of cams for coöperating with said rocker arms, servo motors arranged at the opposite ends of said cam shaft for shifting it longitudinally in opposite directions, devices for governing the medium used to actuate said motors, a reversing member, means operated by said reversing member for turning said rocker arm shaft so as to render the rocker arms inoperative and for thereafter actuating one of the devices that controls the operating medium for one of the servo motors so as to cause said motor to shift the cam shaft longitudinally, a controlling member for the engine, and an interlocking mechanism between said controlling member and reversing member that prevents the reversing member from being operated without first moving the controlling member to cut off the supply of fuel to the engine and for preventing said controlling member from being operated when the reversing member

- is being moved to change the direction of rotation of the crank shaft of the engine. 55
20. An internal combustion engine, comprising rocker arms or valve operating devices, an eccentrically mounted shaft on which said rocker arms are fulcrumed, a shiftable cam shaft provided with two sets of cams for coöperating with said rocker arms, servo motors arranged at the opposite ends of said cam shaft for shifting it longitudinally in opposite directions, devices for governing the medium used to actuate said motors, a reversing member, means operated by said reversing member for turning said rocker arm shaft so as to render the rocker arms inoperative and for thereafter actuating one of the devices that controls the operating medium for one of the servo motors so as to cause said motor to shift the cam shaft longitudinally, a controlling member for the engine, and coöperating devices combined with said controlling member and with said reversing member and constructed in such a manner that said controlling member can not be moved when said controlling member is in an improper position and said reversing member can not be moved when said controlling member is in an improper position. 60
21. An internal combustion engine, comprising a cam shaft provided with a double set of cams, rocker arms adapted to coöperate with said cams, an eccentric shaft on which said rocker arms are fulcrumed, means for locking the cam shaft in two positions so as to hold either set of cams in alignment with said rocker arms, means for successively unlocking the cam shaft and simultaneously turning the rocker arm shaft so as to move the rocker arms into an inoperative position with relation to said cams, means for shifting the cam shaft longitudinally and for thereafter relocking the cam shaft and restoring all of the rocker arms to operative relationship with one set of cams on the cam shaft. 65
22. An internal combustion engine, comprising rocker arms or valve operating devices, a cam shaft composed of a plurality of sections, a coupling device for joining said sections together, and mechanism for transmitting movement from the crank shaft of the engine to said cam shaft comprising 70
- a hollow gear that incases said coupling device. 75
23. An internal combustion engine provided with a cam shaft that is adapted to be shifted longitudinally when it is desired to reverse the engine, servo motors arranged at the opposite ends of said shaft for moving said shaft longitudinally in opposite directions and arranged so that one motor acts as a dash pot to retard the movement of said shaft when it is being shifted by the other motor, and a reversing member for controlling the operation of both of said servo motors. 80
24. An internal combustion engine, comprising a cam shaft that is adapted to be shifted longitudinally to change the direction of rotation of the crank shaft of the engine, a locking device for said cam shaft that is capable of holding said shaft in either one of two positions, a reversing member, a connection between said reversing member and locking device, means controlled by said reversing member for shifting said cam shaft longitudinally, said locking device being so constructed that it will prevent said reversing member from being moved to its final position before the cam shaft completes its movement in one direction, and a visual indicator combined with said cam shaft for indicating the position of said cam shaft. 85
25. An internal combustion engine provided with a shiftable cam shaft, a housing for said cam shaft, and servo motors carried by said housing for shifting said cam shaft longitudinally. 90
26. An internal combustion engine provided with rocker arms, a shaft on which said rocker arms are fulcrumed, an operating mechanism for said rocker arms, and means for rotating and bodily shifting said shaft so as to render said rocker arms inoperative with respect to said operating mechanism. 95
27. An internal combustion engine provided with rocker arms, an eccentrically mounted shaft on which said rocker arms are fulcrumed, an operating means for said rocker arms, and means for turning said rocker arm shaft so as to render said rocker arms inoperative with relation to said operating means. 100

REINHARD HILDEBRAND.
